UNITED STATES PATENT OFFICE.

SAMUEL KAYE, OF COLUMBUS, MISSISSIPPI.

COOLER FOR BOTTLED GOODS.

Application filed May 25, 1922. Serial No. 563,527.

REISSUED

To all whom it may concern:

Be it known that I, SAMUEL KAYE, a citizen of the United States, residing at Columbus, in the county of Lowndes and State of Mississippi, have invented certain new and useful Improvements in Coolers for Bottled Goods, of which the following is a specification.

My invention relates to an improvement 10 in coolers for bottled and other sealed goods.

The object is to provide a device composed of few, simple and inexpensive parts that can be placed in any ice-box or refrigerator or other receptacle, the invention including 15 means for facilitating receiving, moving forward and removing the articles to be cooled.

My invention consists in a channel or cell adapted to receive bottled or other sealed goods, a movable chute leading thereto, and 20 in position to be moved to shove the articles through the chute, and a container for ice adapted to keep the articles, their contents and the surrounding fluid cool, and, at the same time, to close the chute.

25 In the accompanying drawings:—

Fig. 1 is a vertical longitudinal section;

Fig. 2 is a plan view;

Fig. 3 is an end view with a portion broken away;

30 Fig. 4 is a transverse sectional view;

Fig. 5 is a horizontal section on the line 5—5 of Fig. 1;

Fig. 6 is a side view of the chute;

35 Fig. 7 is an edge view taken at right-angles to Fig. 6;

Fig. 8 is an end view of the cover for removing the articles;

Fig. 9 is a bottom plan view of the same; and

40 Fig. 10 is a perspective view of the cell or channel.

A, represents a cell or channel, preferably, although not necessarily, made of a single sheet of metal fashioned to accommodate a 45 single row of bottles or other sealed goods.

In the construction illustrated, the sides are more or less cut out, as at 1, through the center, leaving the ends 2 somewhat higher, and having shoulders 3 adjacent to the inner 50 sides thereof at a point above the tops of the bottles B, as shown in Fig. 1.

The numeral 4 represents the chute which is removably supported in one end of the cell or channel by means of a hook 10 which rests

upon the edge of the former, constituting a 55 pivot. The bottles or other articles to be cooled are inserted through this chute, and a slot 7 formed in the lower end of the inner wall thereof has a curved lower edge 8, the slot affording lateral clearance for the bottle 60 or other article to prevent its striking the next or preceding bottle-neck with too great force, the curved lower end of the slot catching the bottom of the bottle or other article and "breaking its fall." 65

The inner side 5 of the chute normally stands perpendicular, and in alignment with the inner open edge of the end of the channel or cell, and the extreme upper end of the chute may terminate in a handle 6, if desired, for the easy manipulation of the chute.

A removable cover 11 is adapted to fit and close the open top of the opposite end of the channel or cell, as shown in Fig. 1, and it also may have the added function of providing means for the removal of the bottles or other articles, and to this end it has the depending spring jaws 12 as shown in Figs. 1, 5, 8 and 9, which assume a position when the cover is in place to receive the necks of the 80 bottles or other articles when shoved laterally between them or by lowering the cover from above, and allowing the spring-jaws to spring aside and back into contact with the bottle-neck; therebeneath. When the bottle 85 is thus held by the jaws, it is withdrawn with the cover when the latter is lifted from the top of the cell or channel, all of which is fully illustrated in Fig. 1.

The ice, indicated by the letter I, as shown 90 in Figs. 1 and 4, may rest upon a plate or other support, resting upon the shoulders 3, or, as shown in Figs. 1 and 4, it is preferably placed in a container 13, over which a cover 14 is placed, and the entire cell or 95 channel (and as many of them as desired) are placed side by side, usually in a pan or receptacle 15 of sufficient height above the tops of the bottles or other articles to be cooled, the lower end of the ice container 13, and its cover 14, as indicated by the water line in Fig. 1, not only fully to submerge the bottles or other sealed goods, but also to form a water seal for the ice container, thus 100 making the same air-tight, preserve the ice, and at the same time conserve the cold radiating therefrom.

Different varieties of soft drinks might be

inserted in different channels; as a convenient means for identifying them, the label caps C are inserted and held frictionally in a holder 15' formed therefor in the handle 6, 5 at the upper end of each chute and along the handle 16 of each cover, as shown in Figs. 1, 2, 4 and 8.

When the parts are assembled, it will be seen that the cover 14 of the ice or refrigerant container 13 fits and closes the open inner sides 17 of the ends 2, and the open inner side 5 of the chute, thus keeping the same substantially air-tight.

15 The water which submerges the bottles and forms the seal is kept in circulation due to the differences in temperature between the cooled bottle or bottles and the newly-inserted ones.

16 From the foregoing, it will be seen that a simple, inexpensive, efficient device is provided for cooling bottled and other sealed goods. It is understood that this device is of such a form of construction that it can be inserted in an ordinary ice-box or one constructed especially for the purpose, and as many cells or channels may be inserted side by side as the capacity of the ice-box will admit. When so placed, the ice is placed upon a plate resting upon the shoulders or in the container and enclosed by the cover, and when so placed it closes upon the inner sides of the ends of the cell or channel and chute.

17 The intention is to keep each channel or cell filled with bottles or articles to be cooled at all times. This insures one always resting beneath the cover 11, with its neck between the spring-jaws 12. Thus all the operator has to do to remove a bottle is to raise the

18 cover which pulls the bottle from the cell or channel, whereupon the bottle is detached and the cover is replaced. Each time a bottle is thus removed at one end, another bottle to be cooled is inserted at the other end.

19 To do this, the upper end of the chute is pushed back out of normal position, indicated by full lines in Fig. 1 into its abnormal or dotted line position of Fig. 1, its lower end pushing the row of bottles in its path forward. The bottle to be inserted is then

20 lowered into the upper end of the chute, stopping and resting partly in the slot and against the shoulder of the next adjacent bottle, and, upon releasing the chute, the weight and position of the last-inserted bottle causes the chute to return to its normal position and at the same time allowing the bottle to drop into the channel. In other words, the chute is in position to receive an

21 article and it pushes the row of bottles forward, when it is moved out of its normal position, but when moved into its normal position, the chute directs the bottle into the channel. This operation is repeated whenever a bottle is removed.

22 I claim:

1. A cooler for bottled goods including a channel for containing a row of articles side by side in contact therein, and a movable filling chute for receiving articles and normally directing them into the channel, said chute being adapted to be moved out of normal position to engage an article in the channel to move the articles therein forward. 70

2. A cooler for bottled goods including a channel for containing a row of articles side by side in contact therein, and a movable filling chute connected with the channel for receiving articles and when in its normal position directing said articles into the channel to be cooled, said chute having means in 75 position to engage an article in the channel, when the chute is moved out of normal position, to move the articles in the channel forward. 80

3. A cooler for bottled and sealed goods 85 including a channel, and a movable chute connected therewith constructed and arranged to receive the articles to be cooled, and, when moved, to shove them forward in the channel, and a pan in which the channel or cell is placed, and of sufficient height to maintain a level of water to submerge fully the articles contained in the channel. 90

4. A cooler for bottled goods including a channel, and a movable chute connected with 95 the channel and adapted to receive articles and direct them into the channel to be cooled, said chute having means at its lower end for breaking the fall of the article in its descent through the chute, said means comprising a slot, the lower end of which is of a shape to catch the edges only of the bottom of the article. 100

5. A cooler for bottled goods including a channel and a chute detachably pivoted thereto, and constructed and adapted to receive the articles to be cooled, and, when moved out of normal position, to shove the articles forward in the channel, means located at the opposite end of the channel for removing the articles therefrom, the chute having means at its lower end for breaking the fall of the article in its descent through the chute, said means comprising a slot, the lower end of which is of a shape to catch the edges only of the bottom of the article. 110

6. A cooler for bottled and sealed goods including a channel and a chute movably connected therewith, and constructed and adapted to receive the articles to be cooled, and, when moved out of normal position, to shove the articles forward in the channel, means located at the opposite end of the channel for removing the articles therefrom, the inner edge of the chute being open and perpendicular when in normal position, and a refrigerant container supported over the channel and against one wall of which an open side of the chute rests when in normal position forming a closure for the latter. 120 125 130

7. A cooler for liquid and sealed goods including a channel reduced in height through the center, and the ends having open inner walls and supports at the lower ends of the open portions, a bottle chute located at one end with an open inner side, the edges of which are perpendicular and in alignment with the open edges of the adjacent portion of the channel, and an ice container adapted to rest upon the supports and form a closure for the open inner sides of the ends of the channel and the chute.

8. A cooler for bottled goods including a channel, and a movable chute adapted to receive the articles and when moved in one direction to shove the articles forward in the channel preparatory to the reception of the next article.

9. A cooler for bottled goods, including, in combination, a channel, a movable, open-sided bottle chute which has the double function of receiving the bottles, and, when moved in one direction, of shoving the bottles forward out of the way preparatory for the reception of the next bottle, and an ice-container which closes the open side of the chute when the parts are in their normal position.

In testimony whereof I affix my signature.

SAMUEL KAYE.
